WASHING MACHINE

Penrose R. Hoopes, Philadelphia, Pa., assignor
to Havelet Corporation, a corporation of Connecticut

Application June 23, 1937, Serial No. 149,800

5 Claims. (Cl. 68—184)

This invention relates to washing machines and more particularly to such machines for use in laundries, institutions, dry cleaning establishments and the like where larger amounts of wash are handled at one loading than is the case in the average household.

An object of the invention is to provide a washing machine that may be easily loaded and unloaded.

10 Another object is to provide a washing machine that will not tear delicate fabrics and in which there is no mechanism in the tub or basket.

A further object is to provide a washing machine embodying the principles of operation disclosed in Patents No. 1,775,554 dated September 9, 1930, 1,783,415 dated December 2, 1930, and 1,897,953 dated February 14, 1933 and constituting an improvement thereover in respect to the details of construction herein disclosed.

20 Other objects will be apparent from the following specification, wherein is shown by way of illustration, a preferred embodiment of the invention. Many changes can, however, be made in the construction herein disclosed, without departing 25 from the appended claims.

In the accompanying drawings:

Figure 1 is a top view of a washing machine embodying this invention.

Figure 2 is a side view on the line 2—2 of Figure 1.

Figure 3 is an end view on the line 3—3 of Figure 1.

Figure 4 is an end view on the line 4—4 of Figure 1.

Figure 5 is a sectional view on the line 5—5 of Figure 1.

Figure 6 is a sectional view on the line 6—6 of Figure 1.

Figure 7 is a sectional view of the tank on the line 7—7 of Figure 6.

Figure 8 is a sectional view of the tank on the line 8—8 of Figure 6.

Figure 9 is a sectional view of the tank on the line 9—9 of Figure 6.

Figure 10 is a sectional view of the tank on the line 10—10 of Figure 6.

Figure 11 is a sectional view of the tank on the line 11—11 of Figure 1.

Figure 11a is a sectional view of the tank on the line 11a—11a of Figure 11.

In general this washer comprises a tank, basket or receptacle adopted to contain the material to be washed (hereafter termed "wash") mounted to swing in a stationary frame to facilitate loading and unloading. The "wash" may be anything

such as clothing, vegetables or articles of various kinds.

Any suitable liquid can be used, and hereafter when "water" is referred to it will be understood that any suitable fluid is meant, depending upon the nature of the material to be washed, cleaned or treated. For example, if the washer is used for cleaning clothes, such as men's suits or women's dresses, any of the well known carbon tetrachloride compounds could be used instead of water. If ordinary washing is to be done, ordinary soap and water may be used and for the sake of illustration, a machine will be described suitable for use by laundries and the like, wherein the tank has a capacity of about 210 gallons and the circulating pump has a capacity of 300 gallons per minute at 20 pounds to the square inch pressure. The machine herein described will weigh about 1,000 pounds and the movable tank will weigh about 332 pounds. These figures are given merely to indicate the relative difference in size between such washers and those commonly employed for household use, and indicate the necessity of providing means for moving the tank to facilitate loading and unloading it with wash.

In order to thoroughly wash soiled clothes, the water must be rapidly and vigorously forced through the meshes in the cloth many times to thereby carry away the loosened soil or dirt. To do this in a short space of time is one of the objects of this invention. It has been found that dirty clothes may be thoroughly and quickly cleaned, with the minimum of wear, by the rapid movement of streams of soapy water under pressure introduced to the tank in several different directions at the same time, one or more of which streams flows upwardly. For instance, surprising results are accomplished with this machine by simultaneously introducing the liquid in (1) upwardly directed streams through inlets located at the bottom of the tank, (2) in horizontally directed streams through inlets located at one side of the tank, and (3) downwardly directed streams through inlets located at one side. This subjects the clothes to counteracting forces from three or more different directions in the form of streams of water which forcefully and rapidly pass through them. The soiled clothes are repeatedly penetrated with suds as they are vigorously pushed upwardly by the vertical streams from the bottom, and while ascending come in contact with the horizontal streams which tend to push them sidewise. As the horizontal streams of water pour through the clothes, their tendency to push the clothes sidewise is at first partly coun-

teracted by the upward motion previously imparted to the clothes, and this clash of streams tends to hold them momentarily in a fixed position, and the horizontal streams of water are forced through the clothes much oftener and much more forcibly than when they are not subjected to counteracting streams; for instance, as when they follow an even circular path around the tank. The horizontal streams push the clothes over to the opposite side of the tank where the downwardly directed streams push the clothes to the bottom again and here they encounter other horizontal streams which push them into the upwardly directed streams, and the same action is repeated. The clothes follow a somewhat irregular path, and the three or more sudden changes in the direction of their movement serve to vigorously force water through them rapidly and repeatedly as they are moved about.

20 The machine framework may include a base 12 forming a tank or chamber 13 communicating via pipe 14 with the intake of a suitable pump 15 which may be directly driven by the motor 16. The pump and motor are mounted on the upright 21 and form a unit with the base 12. The delivery or pressure side of pump 15 connects via pipe 17 to a 3-way valve 18, and a pipe 19 connects this valve to a fitting 20 supported in the upright 21. This fitting extends inwardly through the upright 30 and serves as one of the supports for the wash tank 22 to be presently described.

An upright 23 is mounted on the base 12 and supports a fitting 24 which extends therethrough and cooperates with fitting 20 to support the tank 35 which swings therebetween. A pipe 25 connects fitting 24 with a 3-way valve 26 which connects via pipe 27 to chamber 13 in the base.

The fittings or trunnions 20, 24, support the tank 22 so that it is free to swing thereon and also 40 serve to connect the tank in circuit with the pump 15 whereby valves 18 and 26 being properly set, the pump will circulate water in a closed system through the chamber 13 and tank 22. By providing the pipe connections 28, 29 on the pressure 45 and suction sides respectively of the pump, various combinations of one washer with another and connections for fresh rinse and waste water can be easily effected, the 3-way valves 18, 26 permitting any desired connections to be made.

50 If desired, a pipe 30 may be connected to the suction pipe 27 to permit the addition of any liquid substance to the water during operation and a pipe 31 may also connect to the suction side of the system at any suitable point to permit steam to 55 enter therein, if necessary, to the washing or cleaning operation. These pipes permit chemicals or steam to be introduced to the wash water when the machine is running with a charge of water therein, in circulation in a closed system, the valves 18 and 26 being set to permit this. Under such conditions, the flange connection 29 being piped to a storage tank (not shown) the valve 26 may be turned to permit the contents of the tank 22 to be discharged into the storage tank 60 so as to save rinse water, recover soap, or recover partially spent chemicals.

70 By the arrangement just described, the necessity for flexible hose to the tank 22 for filling or emptying the same is eliminated and the introduction and withdrawal of liquid therefrom in normal operation takes place through the hollow supports 20, 24 which also serve as passages for liquid. The tank or basket 22 will now be described. It may consist of an inner and outer shell of wood or 75 metal, constructed in any suitable manner. A

metal tank is shown in the figures. The outer wall or shell has a front wall 32, a rear wall 32a, a bottom wall 32b, and end walls 32c and 32d. These walls are watertight and imperforate except the trunnion fittings 20 and 24 are secured thereto and form passages therethrough for liquid.

The inner wall of the tank comprises a bottom portion 33 and side and end wall members, to be presently described, and forms, together with the outer shell what may be termed a tank within a tank, the space between the inner and outer walls or shells being divided into a plurality of pressure and suction manifolds, in two sets or groups, as more clearly shown in Figures 7 to 11a inclusive. The pressure manifolds constituting one set being 15 denoted by the letter P and the suction manifolds constituting the other set being denoted by the letter S, it will be understood that all of the P manifolds are connected to the pressure side of the pump via hollow fitting 20 and pipe 19, and all of the S manifolds are connected to the suction side of the pump via the hollow fitting 24 and the pipe 25.

Communicating with the pressure manifolds P and opening into the interior of the tank or basket 25 is a plurality of nozzles or ports arranged in 4 sets as shown in Figure 5. These nozzles may be any suitable type of individually adjustable nozzles, adjustable both for area of stream and the direction thereof. The upper set of nozzles, generally 30 indicated by the numeral 34, is adapted to project streams of liquid horizontally. The lower set, 35, is adapted to project streams vertically. The set of nozzles at 36 project streams at an angle and the set of nozzles 37, located on the inner side wall 35 near the bottom of the tank, are adapted to project streams horizontally. These streams of water, issuing from the various nozzles, cause the contents of the basket to be revolved or tumbled therein in the manner previously described and 40 the arrangement of these streams is such that any ordinary laundry wash is not tangled or matted together, the washing operation being substantially the same as that in prior patents heretofore mentioned with the improvements herein set 45 forth. The water is drained back out of the basket and into the suction manifolds S through a plurality of perforations 38 and 39 in the inner side walls of the tank, and at 66 in bottom 33.

A sump 40 is located at one end of the tank as 50 shown in Figures 10, 11 and 11a so that any liquid or scum remaining in the tank after it is drained down to the lowest point that the perforations will permit, will drain through the openings 41 and 42 and collect in the sump, and can be discharged 55 therefrom via the discharge pipe 43 which is provided with a valve having an upwardly extending shaft 44 with a hand wheel 45 at its upper end. The arrows, Figure 11, show the normal path of wash water through the sump during the washing 60 operation.

The means for raising and lowering the tank will now be described.

A horizontal shaft 46 extends across the bottom of the tank as shown, said shaft being supported 65 in bearings 47 and 48 secured to the bottom of the tank. This shaft has secured thereto gears 49 and 50 which mesh with toothed rails 51 and 52 secured to the uprights 21 and 23. A worm wheel 53 is secured to the shaft 46 and this wheel is 70 engaged by a worm 54 mounted upon the lower end of shaft 55, which shaft has an operating hand wheel 56.

Shaft 55 carrying the worm 54 is mounted upon and moves with the tank, and by turning the 75

wheel 56, thereby rotating shaft 55 and worm 54, worm wheel 53 is caused to turn shaft 46 and the gears 49 and 50 thereon being in engagement with the toothed rails 51 and 52, travel upwardly on said rails and move the tank around an axis formed by the fittings 20 and 24, to the unloading position shown at 51, Figure 11.

By reversing this operation, the tank may be lowered to its normal operating position.

10 Obviously, any suitable means such as an electric motor may be mounted on the tank structure to turn shaft 55 so as to move the tank by power instead of manually.

15 In a machine of the character described, the sludge or scum including much of the dirt, will float up on the top of the water in the tank. To facilitate its removal and permit it to be withdrawn from the tank while the washing is in progress or immediately thereafter before the 20 wash water is drained off, the upper edge of the inner walls of the tank are slotted as shown at 58, on the back to form a comb. The sludge passes through these slots and into the channel 59 along the back, said channel at each side, as 25 shown in dotted lines, Figure 1, terminating in communication with the flanges 60, 61, each of which may connect to a pipe, one of which is shown at 62, and these pipes may have a common connection 63 through which the sludge may be 30 discharged.

That portion of the inner front wall indicated at 64 is not slotted, but is left smooth so it will not interfere with the easy removal of the wash when the tank is elevated as shown in Figure 11 35 as when in this position the wash will slide out of the tank by gravity without much handling or lifting of the wet wash.

40 The top of a tank may be hinged or may slide and is provided with a handle 65 having any suitable locking means to lock the top in open or closed position. As many such arrangements are obvious, it will not be described in detail.

What is claimed is:

1. In a washing device of the class described, a 45 frame having uprights, a pair of hollow fittings mounted on said uprights, a tank supported by said fittings, the interior of said tank being in liquid communication with the interior of said fittings and said tank adapted to swing in the

arc of a circle about said fittings, a shaft secured to the bottom of said tank and extending from side to side thereof and having a gear on each side adjacent the lower edge thereof, means secured to said tank for revolving said shaft and racks secured to said framework and adapted to be engaged by said gear wheels whereby said tank may be swung in various positions about said fittings as an axis. 5

2. In a washing device, a substantially rectangular tank, a plurality of liquid delivering conduits, a plurality of liquid withdrawing conduits, said conduits being arranged alternately to form inner and outer walls of said tank, the inner of said walls having alternate rows of inlet openings 10 from said delivery conduits and of outlet openings 15 to said withdrawing conduits, means to admit liquid to said delivering conduits and means to emit liquid from said withdrawing conduits. 20

3. In a washing device, a tank, a pressure header, pressure conduits connected with said pressure header, a suction header, suction conduits between said pressure conduits and connected with said suction header, said headers and 25 conduits forming the walls of said tank, and means for circulating liquid through said walls and tank, the inner wall of said tank having alternate rows of inlet and outlet openings communicating with said pressure and suction conduits respectively. 30

4. In a washing device, a tank, a plurality of horizontal pressure and suction conduits forming the side walls of said tank, openings in said conduits connecting with the inside of the tank 35 and means for circulating liquid through said conduits, openings and tank.

5. In a washing device, a tank, a pressure header at one end of said tank, a pressure conduit connected to said pressure header, a suction header at the opposite end of said tank, and a suction conduit connected thereto and positioned parallel to the said pressure conduit, said 40 headers and conduits forming the side and end walls and bottom of said tank and said conduits having alternately disposed rows of inlet nozzles 45 and outlet openings through the inner walls thereof.

PENROSE R. HOOPES.
